WEIGHT PRINTING COIN CONTROLLED
SCALE

Vincent F. Slezak, New York, N. Y., assignor to
International Ticket Scale Corporation, New
York, N. Y., a corporation of Delaware

Application November 17, 1930, Serial No. 496,269

4 Claims. (Cl. 265—5)

The invention relates to new and useful improvements in a coin controlled weight printing mechanism.

An object of the invention is to provide a weight printing machine of the above type where-
in the indicating device is moved in synchronism
with the printing wheel by the direct driving
engagement therewith.

A further object of the invention is to provide
a driving mechanism for the indicating device
which imparts positive movement thereto, so that
said indicating device may be utilized for indi-
cating the zero placement of the printing wheel.

These and other objects will in part be obvious,
and will in part be hereinafter more fully de-
scribed.

In the drawings:—

Figure 1 is a vertical sectional view through
the upper portion of the cabinet of a coin con-
trolled weight printing machine embodying the
improvements.

Figure 2 is a vertical sectional view on the line
2—2 of Figure 1 at the central portion of the
cabinet.

Figure 3 is an enlarged detail showing the driv-
ing wheel for the indicating device in section.

Figure 4 is a view showing a slightly modified
arrangement of closing the top member for the
cabinet, and the indicating device used in connec-
tion therewith.

Figure 5 is a view showing on an enlarged
scale the driving mechanism for the indicating
device which imparts positive movements there-
to by each increment movement given the print-
ing wheel.

Figure 6 is a view showing the arrangement of
the zero mark on the indicating device which is
used in connection with this positive drive of the
indicating device.

The invention is directed to a coin controlled
weight printing mechanism. In the preferred
form of the invention the cabinet is of such
height that the person standing on the weigh-
ing platform can clearly overlook and view the
top closing member of the cabinet. The coin
controlled slot is placed in this top member. Also
placed in the top member is a transparent panel
beneath which is located the indicating device
which determines when the elements of the
weighing mechanism come to a standstill. The
weight of the person on the platform is printed
on a ticket by a printing wheel which is posi-
tioned by suitable devices of a well known char-
acter connected to the weighing mechanism. In
the preferred embodiment of the invention this

indicating device is operated through a direct
connection with the printing wheel. The indi-
cating device is mounted in a frame which is in
turn so mounted that it is free to move up and
down, and really merely serves as a supporting 36
guide for the indicating device. The indicating
device is in the form of a flanged disc. The
flange is arranged parallel with the face of the
transparent panel in the top of the cabinet. This
disc is mounted on a shaft which is journaled in 65
the frame. On this frame is a driving wheel
which is preferably provided with a rubber sur-
face, and this rubber surface of the driving wheel
directly contacts with the type face of the print-
ing wheel. This indicating device is arranged 70
above the printing wheel, and therefore the weight
of the indicating device and the guiding frame
causes the driving wheel to frictionally engage
the printing wheel so that it will oscillate back
and forth as the printing wheel oscillates back 75
and forth in coming to a stationary position.
With this type of drive for the indicating device
the zero mark is placed on the type wheel and
a pointer arranged on a fixed part and viewed
through a transparent panel at the front of the 80
machine to indicate a correct zero positioning
of the printing wheel. In the preferred form
of the invention the shaft carrying the indi-
cating device is provided with a gear, and this
gear meshes with a gear rigidly attached to the 85
printing wheel. Thus it is that the indicating
device will be positively driven by the printing
wheel. In this form of the invention the mark-
ings for indicating a correct zero positioning of
the printing wheel are placed on the indicating 90
device and the transparent panel associated
therewith.

Referring more in detail to the drawings, the
invention is shown as embodied in a coin con-
trolled weight printing machine which includes 95
a cabinet or casing 1 which may be of any desired
shape. At the top of this cabinet is a closing
member 2. The cabinet is preferably made of
such height that the person standing on the plat-
form to be weighed overlooks this top member 100
2. In this top member 2 is a coin slot 3 beneath
which is a coin receiving member 4. This coin
receiving member is provided with the usual coin
diverting plate 5. Beneath the member 4 is the
coin receiving chute for directing the coin to the
coin controlled devices for the weight printing
mechanism. In Figure 1 of the drawings the
chute 6 is shown, which receives the diverted
coins and returns them to the person dropping
the coin, provided the machine is not in condition 110

for performing its weighing operation. These features form no part of the present invention, and are merely referred to as showing the location of the coin slot in the cabinet. The weight 5 is printed on a ticket by a printing wheel 7 which is of the usual character. On the peripheral face of this printing wheel is placed the printing type. A printing ribbon passes between the type and the ticket, and when the printing 10 wheel is brought to a stationary position by the person on the platform, the coin is dropped which releases the printing hammer and the ticket is pressed against the ribbon and the ribbon against the type. The printing wheel is, of course, connected to the weighing mechanism so that it is set in a position for indicating and printing the correct weight of the person on the platform. In a spring scale the weighing lever is coming 15 to a fixed stationary position, when the person steps on the platform, vibrates or oscillates back and forth as it comes to this stationary position. Inasmuch as the weighing lever is connected to the printing wheel there is also this same oscillating or vibrating of the printing wheel 20 as it comes to a fixed position for printing. Associated with the printing wheel is an indicating device which indicates to the person on the platform when the printing wheel comes to a stationary position so that the coin may be withheld 25 until the printing wheel is stationary, and thus the correct weight is printed on the ticket. If the printing wheel is vibrating and the coin should be dropped, it is likely to print an incorrect weight. This is a well known operation in 30 a coin controlled weight printing scale of the spring type. The details of the means for operating the printing wheel have not been illustrated as they are well known in the art, and likewise the printing mechanism has not been 35 illustrated in detail. The present invention has to do with the location and the means for operating the indicating wheel. The indicating wheel is shown at 8 in the drawings. It is in the form of a disc 9 having a peripheral flange 10, preferably formed integral therewith. This indicating device is carried by a shaft 11, which shaft has reduced pin trunnions 12 at its ends. The shaft is mounted in a frame 13 consisting of two side members connected by an end member 14. These 40 side members are mounted on a pivot pin 15 carried by a bracket 16 which is secured to the frame of the machine. The frame can oscillate freely on this pivot 15. On the shaft 11 is a driving pulley 17 which is rigidly attached to the shaft, and is also rigidly attached to the disc 9 of the indicating device. This driving pulley 45 17 consists of a metal hub having a flange at its outer end and a rubber or elastic member 18 which encircles the hub and projects beyond the periphery of the flange. The frame 13 is arranged directly above the printing wheel, and the indicating device is mounted therein so as to be located at one side of the printing wheel with the driving pulley resting on the printing wheel, 50 the weight of the frame and the indicating device and also the driving pulley continually forcing said driving pulley into contact with the printing wheel. This produces the necessary frictional gripping contact between the pulley and the printing wheel, so that the indicating device will 55 be turned in synchronism with the printing wheel. As the printing wheel oscillates back and forth, coming to a stationary position, the indicating device will be oscillated back and forth in a similar 60 manner. Inasmuch as the driving pulley is of

relatively small diameter, compared with the peripheral diameter of the indicating device, the movement imparted to the peripheral surface of the indicating device will be greatly multiplied. In other words, if the printing wheel is oscillating back and forth through a relatively small range of movement, the indicating device will be oscillated back and forth through a comparatively wide range of movement, so that even the smallest vibrations of the printing wheel will be clearly indicated by this device, and when the indicating device comes to a standstill the printing wheel is surely at a standstill. The indicating device is located above the printing wheel as noted, and directly below a transparent panel 19 closing an opening in the top member 2 of the cabinet. The peripheral face of the indicating device is provided with some spaced indicating characters which, as shown in the drawings, are in the form of triangle points, and the transparent panel is provided with a line beneath which these points come to a standstill. By having the spaced points preferably colored, any slight movement of the indicating device will be readily determined by the person viewing the same through this panel. 100

In the form shown in Figure 4 there is a slightly modified arrangement of the top panel. It is inclined to the horizontal and contains a coin slot and a transparent panel 19 such as has been described above. The only differences in the 105 structure of the indicating device reside in the arrangement of the peripheral flange thereon. This peripheral flange is shaped as a frustum of a cone with the face thereof parallel to the transparent panel. This peripheral arrangement 110 of the disc is shown at 20 in the drawings.

The driving mechanism for the indicating device, as shown in the drawings, includes operating gears for positively driving the same. A gear wheel 21 is attached to the shaft 11 carrying the 115 indicating device. Attached to the side face of the printing wheel 7 is a gear wheel 32 which meshes with the gear wheel 21. These gears are so proportioned relative to the rubber-covered driving pulley 17 that said pulley supports the 120 weight of the frame and the indicating disc, and serves as a driver for the indicating device. The gear wheels insure a positive movement of the indicating device in synchronism with the movement of the printing wheel. For each increment 125 of movement of the printing wheel there is a similar increment of movement imparted to the indicating device. This indicating device operates in precisely the same manner to show to the person on the weighing platform when the 130 weighing elements are brought to a stationary position for printing. In view of the fact that the indicating device is geared to and positively driven by the printing wheel the correct zero 135 positioning of the printing wheel can be indicated and determined by this indicating device. I have, therefore, placed on the periphery of the indicating device a zero point which is indicated at 23, and have also placed on the transparent panel a line which cooperates therewith. The indicating device is so timed at the initial assembly of the parts that this zero point is exactly on the line when the printing wheel is exactly on the zero line and would print zero indications on the ticket. This zero positioning may be twenty pounds or any other suitable starting point. If it is found that the zero indications are not on the line where they should be when there is no 140 one on the platform, then the machine should be 145

adjusted to bring about correct weight indications.

From the above it will be noted that I have provided a coin controlled weight printing machine which is of relatively small proportions, and wherein the coin slot and the transparent panel through which the indicating device is viewed are both arranged in the top closing plate of the cabinet. It will also be noted that I have provided a coin controlled weight printing device wherein there is an indicating device that is driven directly from the printing wheel, and therefore there is no lost motion in operating parts, but the indicating device is moved in perfect synchronism with the printing wheel when the indicating device is stationary and the printing wheel is also stationary. Furthermore, by my improved method of driving the indicating device there is a multiplied range of movement in the indicating device for each increment of movement of the printing device, and this renders the indicating device much more efficient in determining the stationary position of the printing wheel. Then again by the gearing of the indicating device to the printing wheel, so that it is positively moved thereby, I am able to show through the indicating device whether or not the printing wheel is set at its correct zero printing position when there is no person on the platform.

It is obvious that minor changes in details of construction and arrangement of the parts may be made without departing from the spirit of the invention as set forth in the appended claims.

Having thus described the invention, what I claim as new and desire to secure by Letters Patent, is:—

1. In a weight printing coin controlled scale, the combination of a cabinet, a printing wheel within said cabinet, a transparent panel in the wall of said cabinet, a motion indicating device adjacent the inner face of said transparent panel, a movable frame in which said indicating device is mounted for rotation, a driving pulley connected to said indicating device and bearing against the type face of the printing wheel for supporting and rotating said indicating device, a gear attached to said indicating device and meshing with the gear attached to the printing

wheel whereby said indicating device is positively moved in synchronism with said printing wheel.

2. In a weight printing coin controlled scale, the combination of a cabinet, a printing wheel within said cabinet, a transparent panel in the wall of said cabinet, a motion indicating device adjacent the inner face of said transparent panel, a movable frame in which said indicating device is mounted for rotation, a driving pulley connected to said indicating device and bearing against the type face of the printing wheel for supporting and rotating said indicating device, a gear attached to said indicating device and meshing with the gear attached to the printing wheel whereby said indicating device is positively moved in synchronism with said printing wheel, said driving pulley having an elastic face making contact with said type face and so proportioned relative to the gears as to maintain said gears in loose running contact.

3. In a weight printing coin controlled scale, the combination of a cabinet adapted to house a weight printing wheel, said cabinet having a transparent panel in the top closing member thereof, a motion indicating device disposed above said printing wheel and directly beneath the transparent panel, means operated by the printing wheel for imparting a multiplied movement to said indicating device, said indicating device having a zero mark on the periphery thereof of cooperating with a mark on the transparent panel whereby the correct positioning of the printing wheel may be determined through said indicating device.

4. In a weight printing coin controlled scale, the combination of a cabinet, a printing wheel within said cabinet, a transparent panel in a wall of said cabinet and an indicating device adjacent said transparent wall, a movable frame in which said indicating device is mounted for rotation, driving means connected to said indicating device and having a positive rotating connection with the printing wheel, said indicating device having characters on the face thereof including a zero mark whereby the correct zero positioning of the printing wheel may be determined through said positive connection of the indicating device with the printing wheel.
